US00D830316S

(12) **United States Design Patent** (10) **Patent No.:** **US D830,316 S**
Min et al. (45) **Date of Patent:** **** Oct. 9, 2018**

(54) **SOCKET MODULE FOR AN ELECTRONIC RELAY**

(71) Applicant: **Phoenix Contact GmbH & Co. KG**, Blomberg (DE)

(72) Inventors: **Che Min**, Nanjing (CN); **Sun Degan**, Nanjing (CN); **Kay Lockstedt**, Hameln (DE); **Markus Becker**, Paderborn (DE)

(73) Assignee: **Phoenix Contact GmbH & Co. KG**, Blomberg (DE)

(**) Term: **15 Years**

(21) Appl. No.: **29/540,939**

(22) Filed: **Sep. 29, 2015**

Related U.S. Application Data

(62) Division of application No. 29/479,572, filed on Jan. 17, 2014, now Pat. No. Des. 741,814, which is a division of application No. 29/444,541, filed on Jan. 31, 2013, now Pat. No. Des. 700,898.

(57) **CLAIM**

The ornamental design for a socket module for an electronic relay, as shown and described.

DESCRIPTION

FIG. 1 is a right front perspective view of a socket module for an electronic relay showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken line portion of the figure drawings is included to show portions of the article that form no part of the claimed design.

1 Claim, 6 Drawing Sheets
